UNITED STATES PATENT OFFICE.

HOCKLEY M. THOMAS, OF NEW YORK, N. Y.

PIN.

1,413,506.

Specification of Letters Patent. Patented Apr. 18, 1922.

Application filed November 6, 1920. Serial No. 422,250.

To all whom it may concern:

Be it known that I, HOCKLEY M. THOMAS, a citizen of the United States, and resident of the city of New York, borough of Manhattan, in the county of New York and State of New York, have invented a new and Improved Pin, of which the following is a full, clear, and exact description.

My invention relates to a pin and aims 10 to provide a device of this character more particularly adapted for use in connection with rolls of any material, but more particularly linoleum and oil cloth.

It is a well appreciated fact that it is often 15 impossible for small stores to maintain a large assortment of linoleum, for the reason that quite a bit of clear space must be available in which a roll of this material may be laid upon the floor and the desired quantity of the same unrolled, subsequent to 20 which the same may be severed.

In view of the fact that this material usually comes in six feet widths it will be readily appreciated that a space of at least six 25 feet, and far greater length must be available for permitting a severance of the desired length of material. Thus the space available for the storing and cutting of linoleum is materially reduced by reason of the 30 fact that a great part of the same must be devoted to the purpose specified.

With this in view, I have constructed a device by means of which a certain quantity of the roll of material may be unwound, and 35 if desired, rewound, at the same time being measured as to length, subsequent to which the strip measured may be severed from the main portion of the roll.

All of these operations by the utilization 40 of my device are permitted, while the roll is in upright position, so that the space heretofore devoted to the "laying out" of the material may now be utilized for storing additional rolls of the same.

45 A further object of my invention is the construction of an appliance of this nature which will serve to more fully support a roll of material while in its upright position so as to prevent the free end of the roll from 50 projecting to any great extent beyond the body portion of the same.

A still further object of my invention is the construction of a pin, which although 55 primarily intended for use in connection with linoleum, may be utilized to advantage

in association with any desired type of material, which is stored in roll form, and which pin may bear advertising, if this is desired.

With these objects in view, reference is 60 had to the attached sheet of drawings as illustrating one practical embodiment of my invention, and in which—

Figure 1 is a fragmentary side view of a pin constructed in accordance with my invention.

Figure 2 is a bottom plan view thereof.

Figure 3 shows the same in applied position associated with a roll of material, and

Figure 4 is a view similar to Figure 3 but 70 showing the pin being utilized for the purpose desired.

In these views the reference numeral 5 indicates the head of a pin of any desired material, which is provided with a body portion 6, which may be formed with flattened faces 7, capable of receiving advertising matter, if this is desired.

The body portion 6 is provided with a longitudinal slit 8 extending from the base 80 thereof to a point short of the upper end of the same, which slit is adapted to receive the material 9, each half of the body portion overlying one of the faces of the material.

85 In Figure 3 it will be seen that the device has been shown in applied position upon a roll of material, and adjacent the free end of the same. This is the normal position of the parts, and it will be appreciated that the pin will add substantially nothing to the bulk of the same.

If it is desired, however, to measure off a length of material 9, it will be seen that, as in Figure 1, a certain portion of the same 95 may be unrolled, the roll remaining in upright position, the pin slid along the unrolled strip of material for a distance corresponding to the length desired.

It will also be appreciated that as the material is unrolled, that the free end thereof may be rolled up so that the entire operation will require a minimum of space. After the desired length of material has been measured off, it will be appreciated that a severance 105 of the same may be effected by running a sharp instrument along one of the flat faces of the pin.

It will further be seen that it might be difficult to retain the pin in a certain posi- 110

tion upon the material, and with this in view, a pair of spike-like projections 10 of any desirable material may be applied to and project below the lower end of the half 5 sections of the body portions 6 of the same. These spikes will permit the lower end of the pin to grip the surface supporting the material 9, and it will thus be appreciated that the pin may be properly retained in 10 position, and at the same time serve to retain the parts of the roll in position when it is applied as in Figure 3.

Thus I have constructed a device of the character specified, which will permit of 15 the storing and manipulation of rolls of material in a space which may be entirely limited, and which, at the same time, will serve to support these rolls of material when

not in use, in such a manner that they will occupy but a minimum of space.

Obviously numerous modifications of structure might readily be resorted to without in the least departing from the spirit of my invention, which I claim as:

1. A pin, including a body portion formed 25 with a longitudinally extending slit adapted to receive and extend over the entire width of a strip of material, and engaging means secured to the lower end of said pin.

2. A pin, including a body portion formed 30 with a longitudinally extending slit adapted to receive and extend over the entire width of a strip of material, and spikes secured to and projecting below the lower ends of the body portion of said pin.

HOCKLEY M. THOMAS.
